UNITED STATES PATENT OFFICE.

ETSON L. FREESE, OF HIGHWOOD, NEW YORK.

DESIGN FOR AN EASEL.

SPECIFICATION forming part of Design No. 25,723, dated June 30, 1896.

Application filed March 7, 1896. Serial No. 582,268. Term of patent 14 years.

To all whom it may concern:

Be it known that I, ETSON L. FREESE, a citizen of the United States, residing at Highwood, in the county of Ulster and State of New York, have invented a new and original Design for Easels, of which the following is a specification, reference being had to the accompanying drawings, which form a part thereof, in which—

- 10 Figure 1 is a front view of an easel involving my new and original design; Fig. 2, a side view thereof; Fig. 3, a front elevation of a section of one of the sides on an enlarged scale, and Fig. 4 a cross-section thereof.
- 15 The leading feature of my new and original design for easels consists in the upright sides A and transverse braces B, the upright support C, and arm or brace D, extending from the upright support C forward and passing 20 through the transverse braces B, and in the style and formation of these parts, as herein-after described. Each of said parts is formed and designed as if a plurality of strips, each of decreasing width, were placed upon each 25 other, the longitudinal centers of each strip

coinciding with that of the central strip, the last-named being of twice the thickness of any other strip, the front surface having four such strips and the rear surface three strips. The design therefore exhibits the parts having longitudinal right-angled grooves, as shown in cross-section by Fig. 4. I further vary and render ornamental my design by notching the angular edges of said longitudinal grooves, as appears in Fig. 3. All the portions are similarly grooved and notched, the said grooves and notches being in proportion to the size of the parts.

Having thus described my design, what I claim is—

The design for easels as herein shown and described.

In testimony that I claim the foregoing as my invention I have signed my name, in presence of the subscribing witnesses, this 4th day 45 of March, 1896.

ETSON L. FREESE.
